UNITED STATES PATENT OFFICE

JOHN H. STORTZ, OF PHILADELPHIA, PENNSYLVANIA

MACHINE FOR MAKING PASTEBORD BOXES

Application filed November 27, 1928. Serial No. 322,114.

This invention relates to a machine for making pasteboard boxes and more particularly to a mechanism for bending inwardly the edges of a rectangular box so that they 5 will maintain an upright position.

Heretofore it has been customary to provide a pasteboard box with a covering of glazed or decorated paper or the like in one machine and to thereafter manually transfer 10 the box to a machine adapted to bend inwardly the sides thereof so as to maintain them in upright position at right angles to the main portion of the box bottom or lid. The boxes have heretofore been arranged in 15 the side bending machine by hand.

It is an object of the present invention to combine the box covering or lining machine with a machine for bending inwardly the edges thereof, the two machines being driven 20 in synchronism so that the operations will take place in proper sequence. More detailed objects along this line relate to the provision of efficient mechanisms for properly moving the boxes from one machine to the other.

25 Further objects of the invention relate to details of construction of the side bending mechanism whereby the boxes may be automatically placed in proper position between the jaws, and ejected therefrom after the bending operation.

In the accompanying drawings:

Fig. 1 is a sectional view more or less diagrammatic showing the relationship between the two mechanisms mentioned above and illustrating the means for driving the two in synchronism.

Fig. 2 is a section on line 2—2 of Fig. 1.

40 Fig. 3 is a top plan view of the bending mechanism.

Fig. 4 is a vertical section showing details of the bending mechanism.

45 Fig. 5 is a plan view of the cam disc for actuating the jaws, showing the supporting shaft thereof in section.

Fig. 6 is a sectional detailed view on line 6—6 of Fig. 1.

Fig. 7 is a diagrammatic sectional view illustrating the mode of operation of the side bending jaws.

The machine which is adapted to place on the pasteboard boxes the glazed or decorated paper cover is shown diagrammatically at 2. Since the details of mechanisms of this sort are well known and this invention is adapted to any of the usual forms, the same is not described fully. There is present in this machine a vertical movable table member 4 on which the pasteboard box indicated at 6 is carried during the covering process. Upon completion of the covering process, the table 4 occupies a position such as illustrated in Fig. 1, while the box is supported thereon in upright position.

Plunger 8 is mounted to reciprocate in suitable bearings in the frame of machine 2 in alignment with box 6 when it is in its final position illustrated in Fig. 1. Plunger 8 is urged in a forwardly direction by means of a spring 10, one end of which abuts the frame 65 while the other end engages a block 12 carried by the plunger, which block is engaged in a slot in the end of a bell crank lever 14 which is provided with a cam roller arranged to engage the periphery of cam 16. A stop 70 75 18, which is preferably provided with a rubber or other soft face to take up shock, is carried by a rear end of plunger 8. Cam 16 is carried by a vertical shaft 20 which is driven through suitable mechanism in synchronism 80 with the other parts of machine 2. Cam 16 is provided with a tapered portion as shown.

As rotation of shaft 20 brings this depression into alignment with the cam roller on lever 14, spring 10 produces a sudden forward 85 movement of the plunger, which engages box 6 and forces it from table member 4 upon a suitable chute which will be hereafter described.

The side bending machine comprises a 90

table 22 in which are formed slides 24 providing guideways for sliding blocks 26 which have inwardly and upwardly extending faces 28 providing box engaging jaws. Extending 5 downwardly from each lock 26 is a pin or roller 30 engageable within a slot 32 in a disc 34. As illustrated in Fig. 5, slots 32 extend eccentrically with respect to the center of rotation of disc 34. Accordingly, oscillation 10 of disc 34 produces simultaneous inward or outward movement of the blocks. Jaw portions 28 are preferably adjustable lengthwise of the box so as to take care of boxes of different sizes. When the jaws operate, the box 15 lies on table 22 between the same and the jaws move inwardly, engaging the central portions of the sides of the box, bending the same inwardly, as illustrated in Fig. 7, thus removing from the sides their tendency to spring 20 outwardly which they normally have after removal from the preceding covering machine.

Disc 34 is carried by a vertical shaft 36 having suitable bearings in the machine 25 frame. Shaft 36 is provided with an arm 38 which is connected by a link 40 with a crank connected to one of a pair of bevel gears 42, the other gear of which pair is secured to a shaft 44 driven by means of a universal connection 46 and bevel gears 48 from shaft 20. By this means, the mechanisms of the two machines are driven in proper synchronism, the inward motion of the jaws taking place subsequently to the discharge of a box from 35 the covering machine when such box reaches its proper position.

In order to properly guide the box after its discharge from the covering machine, upwardly extending guide plates 50 are provided on the side bending machine, these plates being adjustable on rods 52 to accommodate the varying sizes of boxes. Positioned between plates 50 and also adjustable along one of rods 52 are chute members 54 40 on which are mounted, on horizontal axes, rollers 56 which extend above the tops of members 54 and engage a box moving downwardly thereover, thus providing an anti-friction conveyor for the box. This anti-friction feature is found to be important, since it is found that if an attempt is made to slide a box down a metallic chute in damp weather, the friction is so increased as to prevent positive and proper feeding of the 50 box. Members 54 are pivoted at their lower ends to members 58, adjustable on rod 52, and are provided with slots in which may be adjustably engaged the upper ends of levers 60, the lower ends of which are pivoted to 55 members 58, as illustrated in Fig. 1.

A suitable stop means 61 is carried by either both of members 54 or one of them in order to properly position the rear end of a box sliding downwardly over the chute after the forward 60 end thereof has engaged a stop 62 which is

adjustable in a slide mounted on transverse rod 52. By means of stops 61 and 62, which may be adjustable toward and from each other in order to take care of varying thicknesses of boxes, and also by reason of the adjustability of guides 50 and members 54, a box delivered by the chute will fall into proper position between jaws 28, these jaws being in outer positions upon such delivery. Accordingly, it will be observed that the operation taking place in machine 2 is automatically followed by discharge of the box therefrom and its automatic placement in position between the jaws, this action being in turn automatically followed by inward movement 70 of the jaws to produce the proper bending of the sides.

In order to further produce an automatic action, there is provided a mechanism for automatically discharging the boxes after the sides thereof are bent and after jaws 28 have receded from their operative position. In order to accomplish this, a small table or plate 64 is provided on top of a suitable plunger so as to lie flat upon table 22 during the bending operation, but which may be lifted thereabove to raise the box clear of jaws 28 subsequent to such bending operation. The rod which carries plate 64 is provided at its bottom end with an outwardly 80 extending arm 66 to which is connected a link 68 pivoted to a lever 70. Lever 70 is provided with a cam roller which is maintained by the spring 71 in engagement with a cam 72. Rotary motion of cam 72 will 90 thus produce an upward movement of plate 64 to raise the box from the jaws. The rod carrying plate 64 extends downwardly within shaft 36, which is provided with a suitable tapered slot in the side thereof so as to permit free upward and downward movement of arm 66 and also so as not to interfere with this arm and move the same during rotary movement of shaft 36.

Lever 70 is freely mounted upon shaft 74 100 mounted in the frame, one end of which shaft 74 carries a lever 76 provided with a cam roller arranged to engage the periphery of a cam 78 mounted on shaft 44, on which shaft 110 is also mounted cam 72. The other end of shaft 74 is provided with an arm 80 to which is secured a rod 82 normally pressed downwardly to maintain the follower in engagement with cam 78 by means of spring 84. The upper end of rod 82 is connected to a 115 horizontally extending arm of a bell crank lever 86, the upwardly extending arm of which is connected by means of a link 88 with a lever 90 pivoted upon a vertical pin and secured to the frame. Arm 90 is adapted 120 to move in the horizontal plane to which the box is raised by upward movement of plate 64. Accordingly, when the cam roller carried by arm 76 drops into depression 91 125 in the face of cam 78, lever 90 is given a 130

- sharp movement into engagement with the box, throwing the same sidewise on to a suitable conveyor free of the side bending machine so as to clear the same for the entrance of another box. The end of lever 90 which is secured to link 88 is formed so as to be adjustable along the link, thereby providing for an inward or outward movement of the operative end of lever 90 in order to properly accommodate boxes of varying sizes.
- From the above description, it will be clear that there is provided a combined automatic machine which operates upon the box and automatically acts to discharge the same. It will be clear that numerous changes may be made in the specific mechanism shown without departing from the spirit of the claims.
- What I claim and desire to protect by Letters Patent is:
1. In combination, means for forming a pasteboard box, means for bending inwardly the sides of a box including a plurality of movable jaws, and means for automatically transferring a box from the forming means to a position between said jaws, said means including a sloping chute device provided with anti-friction means arranged to contact with a box.
2. A machine for bending inwardly the sides of a box including a plurality of movable jaws, and means for ejecting from between said jaws a box acted upon thereby, said ejecting means including a member for lifting the box from between the jaws and a second member for moving transversely a box so lifted.
3. A machine for bending inwardly the sides of a box including a plurality of movable jaws, means for aligning a box in proper relationship with said jaws to be acted upon thereby, and a chute for delivering a box to said aligning means, said chute being provided with anti-friction devices arranged to contact with a box.
4. A device, comprising a table adapted to receive and support a box, means movable laterally with respect to said table and operative to flex the sides of a box upon said table inwardly, and means to remove said table and a box supported thereby free from the plane of movement of and after said flexing means have withdrawn from operative position.
5. In a box shaping machine, the combination of an elevatable table, box flexing means movable laterally with respect to said table, means to actuate said flexing means and to elevate said table when said flexing means are in inoperative position, and means also actuated by said last-named means to engage and remove a box from said table when in raised position.
6. A device, comprising a table adapted to receive and support a box, means movable laterally with respect to said table and op- erative to flex the sides of a box upon said table inwardly, means to remove said table and a box supported thereby free from the plane of movement of and after said flexing means have withdrawn from operative position, and means to automatically remove a box from said table.
7. A device, comprising a table adapted to receive and support a box, means movable laterally with respect to said table and operative to flex the sides of a box upon said table inwardly, means to remove said table and a box supported thereby free from the plane of movement of and after said flexing means have withdrawn from operative position, and oscillatory means operative to move transversely of said table to move a box therefrom.
8. A device, comprising a table adapted to receive and support a box, means movable laterally with respect to said table and operative to flex the sides of a box upon said table inwardly, means to periodically raise said table and a box supported thereby freely above the plane of operation of said flexing means, and means operative to engage and remove a box from said table when in raised position.
9. A device, comprising a table adapted to receive and support a box, means movable laterally with respect to said table and operative to flex the sides of a box upon said table inwardly, means to periodically raise said table and a box supported thereby freely above the plane of operation of said flexing means, and oscillatable means operative to move across said table when in raised position and to remove a box therefrom.
10. The combination of a box wrapping machine, and a box shaping machine having an elevatable table, with laterally movable flexing means, common operating means for said wrapping and shaping machines, said shaping machine being provided with means driven by said operating means to raise said table freely of said flexing means, and means also actuated by said operating means to remove a box from said table when in raised position.
11. In a box shaping machine, the combination of a table, box flexing means movable laterally with respect to said table, means to actuate said flexing means and to alter the elevation of said table when said flexing means are in inoperative position, and means also actuated by said last-named means to engage and remove a box from said table when out of normal operative elevation.
12. A machine for bending inwardly the sides of a box including members for acting on the sides, devices for relatively moving a box and the members to produce flexure of the sides by contact with the members, and means for ejecting a box from the machine, said ejecting means including a member for

removing a box from the position wherein flexure of the sides occurs.

13. A machine for bending inwardly the sides of a box including members for acting on the sides, devices for relatively moving a box and the members to produce flexure of the sides by contact with the members, and means for ejecting a box from the machine, said ejecting means including a member for removing a box from the position wherein flexure of the sides occurs, and a second member for moving transversely a box so removed.

10 15 In testimony of which invention, I have hereunto set my hand at Philadelphia, Pennsylvania, on this 12th day of October, 1928.

JOHN H. STORTZ.
